SHOE SHINE KIT

Neal Hageal, 1105 Fairoaks Place, New Kensington, Pa., and Edward J. Caputo, 1500 Beachwood Ave., Pittsburgh, Pa.

Filed Dec. 14, 1960, Ser. No. 63,227

Term of patent 14 years

(Cl. D9—2)

Fig. 1.

Fig. 2.

Fig. 3.

FIG. 1 is a top perspective view of a shoe shine kit showing our new design;

FIG. 2 is a bottom perspective view thereof taken from the diagonally opposite side; and

FIG. 3 is a top perspective view thereof showing the lid in the open position.

We claim:

The ornamental design for a shoe shine kit, substantially as shown.
